UNITED STATES PATENT OFFICE.

THOMAS HANS, OF ANDERSON, INDIANA, ASSIGNOR TO MID-WEST BOX COMPANY, OF ANDERSON, INDIANA, A CORPORATION OF INDIANA.

GARMENT-PROTECTOR.

1,216,684.

Specification of Letters Patent. Patented Feb. 20, 1917.

Application filed August 9, 1915. Serial No. 44,409.

To all whom it may concern:

Be it known that I, THOMAS HANS, a citizen of the United States, residing at Anderson, in the county of Madison and State of Indiana, have invented a new and useful Garment-Protector, of which the following is a specification.

The object of my invention is to produce a garment bag suitable for the reception either temporarily or for storage, of garments, the construction being such that the bag may be produced readily from sheet paper and easily folded in an air-tight and bug-proof manner.

The accompanying drawings illustrate my invention. Figure 1 is a perspective view of the bag in use; Fig. 2 an elevation with some portions broken away and other portions turned back, illustrating one form of my improved bag; Fig. 3 a section on line 3—3 of Fig. 2; Fig. 4 a section on line 4—4 of Fig. 2; Fig. 5 a section similar to Fig. 4, showing the protective flap draw outwardly to facilitate the insertion of a garment; Fig. 6 a fragmentary section on line 6—6 of Fig. 2; Fig. 7 a fragmentary section on a larger scale and on a line a trifle below line 6—6 but parallel thereto; Fig. 8 a perspective view of a bag of modified construction; Fig. 9 a transverse section of the bag shown in Fig. 8; Fig. 10 a fragmentary sectional detail of the hanger forming a part of my bag; Fig. 11 a fragmentary perspective section transversely of the bag shown in Fig. 8; and Fig. 12 a fragmentary perspective detail on the line 12—12 of Fig. 2.

In the Figs. 1 to 5, 12 indicates a main body sheet folded longitudinally on the line 13 to form front and back sheets. The upper edges of the doubled sheet are then folded over together and, after the pliable metal strip 14 is laid in position, the edges are again turned down and glued and secured in place by staples 15, the said staples also holding the metal strip 14 in place. The vertical edges are turned inwardly as indicated at 18 and pliable metal strips 19 secured beneath the inturned edge. At intervals in the length of the front or back there are embedded transverse pliable metal strips 20, preferably protected by coverings 21. Upon the inner face of one side of the bag is secured a strip or flap 22, said flap being secured adjacent the free edge of the main body

sheet and normally extending inwardly, as 55 clearly shown in Figs. 2 and 4. This flap should preferably be of considerable lateral extent for a purpose which will appear. The lower edge of the body sheet is turned upwardly and inwardly at 23 and, in order 60 to close the lower end of the bag while at the same time permitting considerable extension, I insert a bottom-forming strip 24 which is doubled and attached at its upwardly presented free edges, as indicated at 65 25, to the inner faces of the body sheet.

Inserted between the doubled upper edges of the body sheet from between the two halves of the body sheet is a loop 30 which may very conveniently be formed of strong 70 fabric and this loop is securely fastened in place by means of a rivet 31 passing through a metal clip 32 which straddles the doubled upper edge of the body sheet and forms an eye for the reception of a hanger hook 33. 75 Loop 30 is of such character as to readily receive the hooks 34 of one or more ordinary garment hangers 35 and, as the loop 30 is directly fastened to the external hook 33 and in line therewith, it will be readily apparent 80 that none of the weight of the garments placed within the bag will come upon the body sheet but will, instead, be directly supported by the hook 33.

The form shown in Figs. 8 to 11, inclusive, is very similar to that shown in the other figures, differing in the following particulars:

The lower end of the bag is closed by having its lower edges turned upwardly, as indicated at 41, and secured in place by suitable staples 42. The flap 43 is similar to flap 22, but conveniently is integral with the body sheet 12.

For ordinary storage purposes, the bag 95 may be hung in a closet by means of its hook 33 and the vertical edge of the bag left freely open, the flap 22 or 43 being withdrawn, as indicated in Figs. 5 and 1, for the ready insertion of a garment in the manner 100 indicated in Fig. 1, whereupon the flap may be turned back into the bag over the garment, thus quite satisfactorily protecting it from dust for short periods and permitting the ready withdrawal of the garment.

When permanent storage is desired, the open vertical edge of the bag will be doubled upon itself twice in a manner shown in

Fig. 7, the vertical strips 19 serving as gages for readily defining the fold line, and the transverse strips 20 operating to retain the fold in position. By this means a moth-proof closure is obtained in a very easy manner. The strips 14 and 19 which are laid longitudinally serve as fold-defining members which insure an easy folding along defined lines, thus insuring tight closure, and the transverse pliable members 20 serve to retain the parts in folded condition.

I claim as my invention:

1. A garment bag consisting of a main body sheet doubled longitudinally and closed at its upper end, a fold-defining stiffening member carried by said body sheet along one of its longitudinal free edges, and fold-retaining members embedded in the body sheet adjacent and transversely to a longitudinal free edge of the body sheet.

2. A garment bag consisting of a main body sheet doubled longitudinally, a fold-defining stiffening member carried by said body sheet along one of its longitudinal free edges, and fold-retaining members embedded in the body sheet adjacent and transversely to a longitudinal free edge of the body sheet.

3. A garment bag comprising a main paper body of two superposed portions, the upper edges of which are permanently closed together by doubling, a stiffening member laid between the portions of the main body at its upper edge between the doubled portions, a loop arranged between the portions of the main body at its upper end, an external hanging member, and fastening means embracing the upper edge of the main body and permanently connecting the external hanging member and the loop.

4. A garment bag comprising a main paper body of two superposed portions, the upper edges of which are permanently closed together, a stiffening member laid between the portions of the main body at its upper edge, a loop arranged between the portions of the main body at its upper end, an external hanging member, and fastening means embracing the upper edge of the main body and permanently connecting the external hanging member and the loop.

5. A garment bag having a main body of paper comprising two superposed portions, said body being permanently closed at one longitudinal edge, and at the top and bottom, a loop arranged between the portions of the main body at the top, an external hanging member, connections between the external hanging member and the loop of such character that the top has no opening therethrough, and a flap carried by one portion of the main body and having its free edge extended inwardly between the two portions of the main body.

6. A garment bag having a main body of

paper comprising two superposed portions, said body being permanently closed at only one longitudinal edge, and at the top, a loop arranged between the portions of the main body at the top, an external hanging member, connections between the external hanging member and the loop of such character that the top has no opening therethrough, and a flap carried by one portion of the main body and having its free edge extended inwardly between the two portions of the main body.

7. A garment bag having a main body of paper comprising two superposed portions, said body being permanently closed at only one longitudinal edge, and at the top, a loop arranged between the portions of the main body at the top, an external hanging member, and connections between the external hanging member and the loop of such character that the top has no opening therethrough.

8. A garment bag consisting of a paper sheet doubled longitudinally to form a main body, the upper and lower edges only of said doubled sheet being permanently closed, a loop arranged between the portions of the main body at the upper edge, an external hanging member, connections embracing the doubled upper edge and connecting the external hanging member and the loop, and a flap carried by one portion of the main body and having its free edge extended inwardly between the portions of the main body.

9. A garment bag consisting of a paper sheet doubled longitudinally to form a main body, the upper and lower edges of said doubled sheet being permanently closed, a loop arranged between the portions of the main body at the upper edge, an external hanging member, and connections embracing the doubled upper edge and connecting the external hanging member and the loop.

10. A garment bag having a main body formed of a sheet of paper doubled upon itself longitudinally and the upper and lower edges permanently closed, a fold defining reinforcement applied to one of the free longitudinal edges of the body sheet, a flap carried by one of the free edges of the body sheet and having its free edge projected inwardly between the portions of the body sheet, a loop arranged between the portions of the body sheet at the upper edge, an external hanging member, and a connection between said external hanging member and the loop.

11. A garment bag having a main body formed of a sheet of paper doubled upon itself longitudinally and the upper and lower edges only permanently closed, a fold-defining reinforcement applied to one of the free longitudinal edges of the body sheet, a loop arranged between the portions of the

body sheet at the upper edge, an external hanging member, and a connection between said external hanging member and the loop.

12. A garment bag comprising a main body of sheet paper having the upper edges thereof arranged to form a permanent closure, a stiffening strip embedded in said upper edge, a loop arranged between the portions of the main body between the same 10 at the upper edge, an external hanging member, and a connection between said external hanging member and the loop.

13. A garment bag having a main body formed of a paper sheet doubled upon itself longitudinally and having its upper edges doubled downwardly upon the main body and permanently inclosing a stiffening strip, a loop arranged between the por-

tions of the main body at the upper edge, an external hanging member, and a connection between said external hanging member and the loop. 20

14. A garment bag having a main body formed of a paper sheet doubled upon itself longitudinally and having its upper 25 edges doubled downwardly upon the main body, a loop arranged between the portions of the main body at the upper edge, an external hanging member, and a permanent connection between said external hanging member and the loop. 30

In witness whereof, I have hereunto set my hand at Anderson, Indiana, this sixth day of August, A. D. one thousand nine hundred and fifteen.

THOMAS HANS.
